UNITED STATES PATENT OFFICE.

LEON BARG, OF NEW YORK, N. Y.

MACHPELAH OR RESTING PLACE FOR THE DEAD.

No. 920,812.

Specification of Letters Patent.

Patented May 4, 1909.

Application filed August 19, 1908. Serial No. 449,260.

To all whom it may concern:

Be it known that I, LEON BARG, a citizen of the United States of America, residing at New York, in the borough of Manhattan, county and State of New York, have invented certain new and useful Improvements in Machpelahs or Resting Places for the Dead, of which the following is a specification.

10 This invention relates to an improved machpelah or resting-place for the dead. Heretofore dead bodies were either buried in graves or in walls or mausoleums. This mode of burial was, however, connected 15 with many objectionable features, partly sanitary, and partly inconvenient on account of the increasing population.

The object of this invention is to supply a resting-place or machpelah for the dead, in 20 which comparatively a large number of dead bodies can be stored and preserved within a comparatively narrow compass in an entirely unobjectionable manner from a hygienic standpoint; and for this purpose 25 the invention consists of a machpelah or resting-place for the dead, which is constructed of concrete with a number of compartments arranged in tiers, one above the other, said compartments being closed at 30 the rear-ends and inclosed at the front-ends by a hermetically-sealed cover. Ventilating channels are arranged in the upright walls between the individual compartments and in the bottom of the structure, the partition 35 walls being made double so as to form the upright ventilating channels.

The invention consists further of certain details of construction, and more especially relating to the construction of the sealed 40 cover for the compartments, as will be fully described hereinafter and finally pointed out in the claims.

In the accompanying drawings, Figure 1 represents a perspective view of my improved machpelah or resting-place for the dead. Figs. 2 and 3 are respectively a horizontal section and a vertical section respectively on lines 2, 2, and 3, 3, Fig. 1, Fig. 4 is a detail horizontal section of the sealing end of one of the compartments, and Fig. 5 is a horizontal section, drawn on a larger scale, of a modified construction of the sealing end of one of the compartments.

Similar letters of reference indicate corresponding parts throughout the several figures.

Referring to the drawings, *a* represents one of the compartments of my improved machpelah or resting place for the dead. The machpelah is composed of a plurality of compartments, which are arranged in horizontal tiers, any number of tiers being arranged one above the other. Each compartment is made large enough to receive a coffin containing a corpse. The rear-end of each compartment is closed, the rear-end of each compartment being separated by vertical transverse partition-walls *a*¹ from another set of compartments which are arranged at the back of the front or first set. The compartments are constructed of a number of horizontal and vertical partition walls *a*² *a*³ which are made of concrete and which are built up in connection with suitable molds, the vertical partition-walls *a*³ being preferably made double, so as to form ventilating-channels *a*⁴. Any number of sets of compartments may be arranged in groups sidewise of and above each other, the whole structure being inclosed by a suitable shed or other structure, or left unprotected, as desired.

The compartments are closed at their rear-ends and open at their front-ends until they are occupied by a coffin containing a dead body. After the coffin is placed on the compartment, a hermetically-closing cover *d* is inserted into the front-end said cover consisting of three parts, a board or plate *d*¹, which is placed against shoulders *d*² at the interior of the compartment, a block *d*³ of concrete which is cast in such a manner as to fill up grooves *d*⁴ at the sides and top of the front-end of the compartment so as to form a tongue-and-groove joint with the same, and a stone or other slab *d*⁵ on which the name of the person in the compartment, dates of birth and death, and other data are inscribed.

In the construction shown in Fig. 5, the cement block *d*⁶ of the cover is cast in a number of grooves *d*⁷. Also, the upright walls *a*⁸ are not provided with ventilating channels.

In the bottom of the groups of compartments are arranged parallel ventilating-channels *a*⁹ which connect with the vertical channels arranged in the double partition-walls *a*³ of the structure. The bottom channels are slightly inclined so as to permit any rain water to be drawn off through the vertical and bottom channels. Likewise any gases of decomposition which may permeate through the porous upright walls of the

structure can be conducted off by the continuous ventilation established through the same.

The vertical channels at the sides of the compartments do not communicate directly with the compartments, but only receive the gases which permeate through the porous imperforate side-walls of the latter, the gases being carried upward to the top-surface of the structure and emitted into the atmosphere by the upper outlet-ends of the channels, which extend substantially throughout the length of the compartments. The individual bottom ventilating channels ^{d*} extend from the front to the rear of the structure below the lowermost compartments and are alined with the respective vertical channels with which they communicate, having their front-ends open to the atmosphere at the base of the structure.

20 After a certain period of time additional compartments are built upon the lower groups of compartments, and in this case the new groups are separated by a horizontal partition-wall provided with ventilating-channels in the same manner as the bottom and vertical partition-walls of the lower groups. Before they are built the double partition-walls and bottom channels of the lower groups are entirely filled with 25 concrete so as to increase the strength of the lower groups and produce the absolute hermetic sealing of the same. Before the compartments are occupied by dead bodies they can be closed by a pane of wired-glass which 30 can be readily removed when the compartment is to be used for a dead body, and which prevents the ingress of dust in the compartment.

The structure described forms a hermetic- 40 ally-sealed machpelah or resting-place for the dead, in which a large number of bodies can be efficiently stored and preserved for an almost indefinite length of time, without contamination of the ground or danger to 45 health. Instead of burying the bodies in the ground, they are stored in a structure above the ground which is always ready for inspection and immediate burial, and in which each compartment can be quickly 50 sealed after the coffin is placed therein, and still ventilated to some extent. It forms a resting-place for the dead similar to the cave or rock-graves of the ancient peoples

as mentioned in the Old Testament, and permits the storage of a large number of bodies 55 in a comparatively small space, which from a sanitary point of view is entirely innocuous and unobjectionable.

Having thus described my invention, I claim as new and desire to secure by Letters 60 Patent:

1. In a burial structure such as described, the combination of a plurality of compartments formed by horizontal walls arranged in tiers, and imperforate porous partition-walls 65 entirely closing the compartments at the sides and each having a channel therein, said channels collecting the gases which pass through the porous side-walls of the compartments and being open to the atmosphere 70 at their upper ends.

2. In a burial structure such as described, the combination of a plurality of upright porous partition-walls having vertical channels or passages therein open to the atmosphere at the top of the structure, horizontal walls supported by said vertical walls and forming in conjunction therewith a plurality of burial compartments arranged in tiers, and separate horizontal ventilating 80 channels in the base of the structure alined and communicating with the respective channels or passages of said partition-walls and having their ends open to the atmosphere at the front of the structure. 85

3. In a burial structure such as described, the combination of a plurality of compartments formed by horizontal walls arranged in tiers, and vertical porous partition-walls entirely closing the compartments at the 90 sides and each having a channel therein, said channels collecting the gases which pass through the porous side-walls of the compartments and being open to the atmosphere 95 at their upper ends, and separate horizontal ventilating channels in the base of the structure communicating with the first-named channels and having their ends open to the atmosphere at the front of the structure.

In testimony, that I claim the foregoing 100 as my invention, I have signed my name in presence of two subscribing witnesses.

LEON BARG.
